HEAD AND SOCKET FASTENER TAPE

Lee Roseman, Newark, N. J.

Application January 25, 1935, Serial No. 3,418

3 Claims. (Cl. 2—265)

This invention relates in general to fastener tape including a strip of fabric having separable fastener elements attached thereto, to be applied to the edges of openings in garments for fastening such edges together. More particularly the invention is directed to such fastener tape embodying so-called snap fasteners or head and socket fasteners wherein the fastener elements are covered or concealed on the face of the strip or piece of material to which the elements are applied, or on the side of the strip which faces the complementary strip when the fastener is in use.

Snap fastener tape is known in the art, as shown by my Patent No. 1,373,452 dated April 5, 1921, and in my copending application Serial No. 660,626 filed March 14, 1933, I have illustrated and described another form of snap fastener tape. In tape of this general type the snap fastener elements are arranged between two plies of material and are secured in position by lines of stitches passing through said plies snugly embracing the fastener elements at their edges or perimeters, the stitches forming pockets between the plies in which the fasteners are enclosed. Each fastener includes two strips of fabric each composed of a plurality of plies, to be secured for example to the edges of a garment opening such as the ends of a corset or brassière, one having head members secured thereon between two plies and the other having socket members to cooperate with said head members and certain of the plies have perforations in register with the respective heads and sockets to permit connection and disconnection of the complementary fastener elements.

Because these structures consist of several plies of fabric, they are bulky and expensive. This thickness or bulkiness of the tape is objectionable when applied to undergarments to be worn beneath thin or sheer lingerie or dresses because the tape causes unsightly protuberances; and moreover the bulky tape is in many cases uncomfortable to the wearer. The cost of the tape is an important item also because a considerable quantity is used in many types of garments and adds materially to the cost of the garments.

Furthermore, because the strength of attachment of the fastener elements to the fabric strip is limited to the ability of the fabric to resist the strains on the fasteners during use and upon separation of the head members from the socket members, sometimes the tension on the fastener elements results in tearing one of the plies of fabric either around the edges of the elements

or on lines transversely of the elements so as to allow the fastener elements to be pulled or detached from the strip. When the fabric tears in this way there is nothing left to hold the fastener element on the strip.

Also it has been considered necessary to have at least one thickness of material at each side of the fastener to assume the strains on the fastener in directions perpendicular to the tapes during closing and opening of the fasteners.

In another form of fastener, the snap fastener elements are sewed on one side of a piece of material by stitches passing through apertures in the fasteners, the fasteners being exposed and the heads and sockets facing away from the material. This form of fastener is highly objectionable because the strains on the fastener elements during use and opening of the fastener are such as to tend to pull the fastener elements away from the material and this results in breaking of the stitches or tearing of the stitches out of the material so as to detach the fastener elements from the material and impair or destroy the fastener. Also, because of this it has been necessary to utilize fastener elements wherein the resistance to separation of the head and socket elements, as by the spring wires in the socket elements, is so weak that the fastener elements can be separated without tearing the material or breaking the stitches. This spring or frictional resistance has been so weak that it has not been adequate to hold the fastener elements together during use, so that the fastener elements easily separate under the normal strains imposed thereon during wearing of a garment to which the fasteners are applied and thereby impair the usefulness of the fasteners or make it impossible to use them.

Therefore a prime object of the present invention is to provide snap fastener tape which shall embody novel and improved features of construction whereby the tape shall be thin and shall contain a small amount of fabric, and the strain on the fastener elements during use shall pull the fasteners toward and into abutting contact with the material instead of away from the material so as to reduce possibility of the fastener elements being torn from the material and to permit use of stronger spring or frictional resistance to separation of the fastener elements, so that the tape shall be thin enough for use on undergarments to be worn beneath thin lingerie and dresses, or for use on such lingerie or dresses, and shall be strong, durable and relatively inexpensive.

A further object is to provide such fastener

tape which shall embody novel and improved features of construction whereby the tape can be used as a binding for the edge of a garment so as to obviate a large number of thicknesses of material at the edge of the garment.

5 Other objects are to provide fastener tape of the character described wherein the fastener elements shall be applied to one side of a strip with their heads or sockets registering with openings in the tape, so that the fasteners can be concealed between the strip and the garment to which the tape is applied and thereby enable the use of a minimum number of plies or thicknesses of material to ensure thinness and flexibility at 10 the edge of the garment; to provide such a tape that can be easily and rapidly produced on automatic machines and eliminate the necessity of and trouble incident to inserting the fastener elements between plies of fabric which has been required with known types of snap fastener tape; and to obtain other advantages and results as will be brought out by the following description.

15 Referring to the accompanying drawing in which corresponding and like parts are designated throughout the several views by the same reference characters.

20 Figure 1 is a composite transverse vertical sectional view through two complementary fastener tapes embodying my invention showing them applied to the edges of a garment.

25 Figure 2 is a similar view showing a modification of the fastener tapes.

30 Figure 3 is a fragmentary perspective view of the fastener tape having the head fasteners.

35 Figure 4 is a plan view partially in horizontal section on the line 4-4 of the structure shown in Figure 1.

40 Figure 5 is a fragmentary perspective view of the head fastener tape shown in Figure 2.

45 Figure 6 is a fragmentary plan view similar to Figure 4 showing a modified manner of stitching the fastener elements on the tape, and

50 Figure 7 is a transverse vertical sectional view through a modified form of the tape.

55 Figure 8 is a fragmentary perspective view of the strip shown in Figure 7 with the fasteners removed.

60 Specifically describing the embodiment of the invention illustrated in Figure 1, the reference characters A and B designate complementary fastener tapes carrying respectively head fasteners and socket fasteners. Referring to the tape A, it comprises a strip 1 of suitable material such as fabric which may be formed of a single 65 ply or a plurality of plies. As shown, the strip comprises one ply of material and a row of fastener elements 2 with engaging portions, in the present instance heads, at their faces to cooperate with complementary fasteners, said fastener elements being secured on one side of the strip with their said faces abutting the strip, and preferably the edges of the strip are folded inwardly at 3 to conceal raw edges when the tape is applied to a garment. The strip has a plurality of openings 4 therethrough, each in register with and to receive the head 5 of one fastener element.

65 The fasteners may be secured to the strip in any suitable way, but preferably are secured by 70 stitches; and for this purpose each fastener has a plurality of apertures 6 to receive stitches, and there is a line of stitches 7 extending longitudinally of the strip, and offset stitches 8 in continuation of the longitudinal line passing through 75 the strip and the apertures 6 in the fasteners.

In applying the fastener tape to a garment, the edge of the garment is preferably turned back as at 10 and the strip is laid over said turned back edge and secured to the garment by longitudinal lines of stitching 12 which pass through the garment and the folded edges of the strip. The strip is applied to the garment so that the fasteners will be located between the strip and the garment.

10 The socket fastener tape B is the same as the head fastener tape A except that socket fasteners 13 are secured to the strip 14 instead of the head fasteners 2, and the strip 14 has openings 15 therethrough each registering with the socket of one socket fastener. The socket fasteners are secured to the strip by stitches 16 which may be identical with the stitches for securing the head fasteners to the strip 1, and the strip is secured to the edge of a garment C in the same manner as the tape A is secured to the other edge of the garment.

15 In use, the two tapes cooperate with each other in known manner, there being one socket fastener for each head fastener, and the complementary head fastener and socket fastener being connected and separated by movement of the head of the head fastener into and out of the socket of the socket fastener.

20 With this construction, it will be observed that the fastener tape is thin and includes a small amount of material. The garment itself serves as a protecting ply to conceal the fasteners whereby an extra ply on the tape for this purpose, as is common in snap fastener tape, is obviated. Therefore, the tape and edge of the garment to which it is applied will produce a 25 minimum of bulkiness so that an undergarment bearing the tape can be worn beneath thin or sheer lingerie and dress without unsightly protuberances produced by the tape. Moreover, the seam or joint between the garment edges formed by the fastener tapes will be flexible so as to produce a minimum of discomfort to the wearer. The tape is inexpensive and easy to manufacture on automatic machines, the difficulty in inserting the fasteners between the plies during 30 the manufacture of the tape, as is required with known formation of fastener tape, being wholly obviated.

35 A modification of the invention is shown in Figure 2 where the head fastener and socket fastener tapes D and E respectively are each formed of a strip of material folded longitudinally to provide two flaps. Inasmuch as both tapes are identical except as to the type of fasteners, I shall describe only one. The strip 17 of each tape is folded longitudinally at 18 to form two flaps 19 and 20. The fasteners 21 are secured on one side of one flap so as to be located between the flaps when they are folded together, and said flap has openings 22 registering with the respective fasteners. The fasteners are shown as secured to the flap by a longitudinal line of stitches 23 and lateral or offset stitches 24 which pass through the flap and apertures in the fasteners. Obviously, only one tape of the 40 type of D or E may be used with one tape of the type A or B instead of using the two tapes of the same type.

45 This form of the invention is especially useful for forming a binding on the edge of a garment 45 so as to keep the number of plies of material to the minimum. In applying the tape to the edge of a garment F, the garment edge is located between the two flaps 19 and 20 as shown in Figure 50 55 50 so that the strip embraces a garment edge, 55 60 65 70 75 80 85 90 95 98 99 100

and the tape is secured to the garment by a longitudinal line of stitches 26 which pass through both flaps and the garment. With the tape so applied, the fasteners are located between the flap to which they are secured and the garment.

5 The stitches 8 firmly secure the fasteners to the strip against movement in all directions. If desired, the stitches 7 may be omitted although 10 they facilitate sewing of the fasteners and restrain tendency of the stitches 8 to ravel or pull 15 out. As shown, preferably the stitches 8 surround or at least partially surround the openings in the strip so as to reenforce the fabric at the edges of the openings and reduce possibility 20 of tearing and fraying of the fabric.

Obviously the flaps 19 and 20 may be composed of more than one ply of material, but it will be observed that in any event the invention provides a binding tape which is simple and inexpensive and which can be applied to a garment edge to provide a flexible fastener of light bulk or thickness. The fasteners can be easily and quickly secured to this form of tape in the same manner in which they are secured to the tape 25 shown in Figure 1.

A further modification of the invention is shown in Figure 6 wherein the lateral stitches 21 for securing the fasteners to the strips are differently arranged from the stitches 8.

30 In Figure 7 the edge portions of the strip 30 are turned back at 31 to form in effect a double ply strip, and the fasteners 32 are located upon the turned back portions and secured to the strip by stitches 33, e. g., like the stitches 8, which 35 pass through the apertures in the fasteners and through both the turned back portions and the main part of the strip. This structure provides a more substantial body of fabric so that there is less possibility of the stitches tearing out of 40 the fabric.

If desired the fastener elements 2 and 13 may be directly applied to a garment without the strips 1 or 14 but with the opening registering with the fasteners formed in the garment.

45 It will be observed that in all forms of the invention, the strains imposed on the fastener elements during use tend to pull the fastener elements toward and into abutting contact with the material so that there will be a minimum tendency for the stitches to pull out or break, and 50 therefore the springs in the socket members, or other means for holding the heads in the sockets may be strong enough to completely resist strains normally tending to separate the fastener elements so that there will be minimum possibility 55 of accidental opening of the fastener or tearing of the fastener elements from the strips. The strains incident to pressing the head and socket elements together to connect them are absorbed 60 by the index finger and thumb of the user and the stitches prevent detachment of the fasteners from the strip, so that plies of material beneath

or behind the fastener elements as heretofore used are not necessary.

With this construction by using a plurality of plies of material, the tape may be made stronger than tape of the known types wherein the fasteners are arranged between plies of material, and with the same overall thickness of the known types. In other words, all of the plies of material being located at one and the same side of the fastener element, give greater strength than known types with no increase in thickness.

5 It should be understood that while I have shown several forms of the invention, this is primarily for the purpose of illustrating the principles thereof and that the details of structure 15 of the tape may be modified or changed without departing from the spirit or scope of the invention.

It is an important feature of my invention that the fastener elements are secured or stitched on 20 one side of the same strip or ply of material that has the openings through which the fastener elements may be connected and disconnected to and from complementary elements on another similar strip or ply of material, and that the 25 fastener elements are arranged with the faces thereof carrying the engaged portions, i. e. heads or sockets, abutting the strip so that strains thereon during use tend to pull the fasteners against the strip rather than away therefrom. 30 Furthermore, the invention permits of the use of fine fabric, such as silk, for the strip instead of the usual cotton fabric, so that the appearance of a garment of fine material need not be marred but may actually be improved by the 35 fastener strip.

Having thus described my invention, what I claim is:

1. A fastener comprising a piece of material, a row of snap fasteners having engaging portions 40 at their faces to cooperate with complementary fasteners and arranged on one side of said piece with their said faces abutting the piece, there being openings through said piece registering with the respective engaging portions, and 45 stitches securing said fasteners to said piece only.

2. A fastener comprising a piece of material, a row of snap fasteners having engaging portions at their faces to cooperate with complementary fasteners and arranged in one side of said piece 50 with their said faces abutting the piece, there being openings through said piece registering with the respective engaging portions, each fastener having apertures to receive stitches, and stitches passing through said apertures and said 55 piece for securing the fasteners on the piece.

3. The fastener set forth in claim 2, wherein said stitches also extend between said apertures in surrounding relation to said openings to reinforce the material adjacent the edges of the 60 openings.

LEO ROSEMAN.
